UNITED STATES PATENT OFFICE.

EDWARD A. LANGENBACH, OF CANTON, OHIO.

DESIGN FOR A CEILING-PLATE.

SPECIFICATION forming part of Design No. 24,456, dated July 2, 1895.

Application filed May 23, 1895. Serial No. 550,454. Term of patent 7 years.

To all whom it may concern:

Be it known that I, EDWARD A. LANGENBACH, a citizen of the United States, and a resident of Canton, county of Stark, State of Ohio, have invented a new and useful Design 5 for a Metallic Ceiling-Plate, of which the following is a full, clear, and exact description, reference being had to the accompanying drawings, making part of this specification.

10 My invention relates to designs for metallic ceiling-plates.

In the accompanying drawings, Figure 1 is 15 an elevation of a plate made according to my design. Fig. 2 is a vertical section of the same.

20 My design consists of a plate which has the general configuration or shape shown in the accompanying drawings and comprises the curved horizontal upper portion A, the curved horizontal lower portion B, and the straight intermediate portion C, connecting the raised 25 portions A B, the first portions being similarly ornamented, while the middle or connecting portion C is distinctively different, as hereinafter described. The said straight portion at regular intervals is formed with cir-

cular projections D, with ornamental central recesses or depressions E, and connected with these projections D are curved ribs F, which pass over and under a series of semicircular 30 ribs G, which are also connected with horizontal borders H. The said curved portions A and B are formed with ornamental portions I at regular distances apart and in line with the projections D, and comprise the radiating ribs 35 K and the curved portions L, extending from near the edges of the plate to the borders H. These portions L consist of scrolls formed with circular and rectangular depressions M. The portions I have their outer ends curved, 40 so as to present an ornamental appearance. The plate is also formed with a series of horizontal and vertical ribs N and rounded ribs O.

What I claim is—

25 The design for a ceiling plate, as herein shown and described.

In testimony whereof I have hereunto set my hand this 17th day of May, A. D. 1895.

EDWARD A. LANGENBACH.
